PERCUSSION FUSE FOR ROCKET-
PROJECTILES

Paul Emile Joseph Denoix, Paris, France, assignor to Sageb, Société Anonyme de Gestion et de Exploitation de Brevets, Fribourg, Switzerland, a corporation of Switzerland

Application December 27, 1937, Serial No. 181,970
In Switzerland December 31, 1936

1 Claim. (Cl. 102—39)

This invention relates to a percussion fuse for rocket-projectiles, which are equipped with a jet propulsion device, and aims at providing a fuse of the foregoing kind which is simple in construction and reliable in operation.

The fuse of the present invention comprises a safety device, the effacement of which is controlled by a locking member projecting from the rear of the body of the fuse and covered by a diaphragm which forms one wall of the combustion chamber of the jet propulsion charge, in such a manner that the pressure generated in said chamber deforms said diaphragms, thus displacing the locking member and setting the fuse ready for action.

Further features and advantages of the invention will become apparent from the following description taken in conjunction with the accompanying drawing which illustrates diagrammatically and by of example one embodiment thereof, and in which:—

Fig. 1 is an axial section of a bomb equipped with a system of jet propulsion and primed by the aid of a fuse according to the invention; and

Fig. 2 is a section, on a larger scale, through the fuse.

In the embodiment shown, the fuse 1 is mounted in the bottom of a bomb 2 containing an offensive charge 3 and separated, by a deformable diaphragm 4, from a combustion chamber 5 containing the jet propulsion charge 6 which discharges into a nozzle 7.

The fuse comprises a body 1 (Fig. 2) mounted in a sheath 8 and provided with a bore 9 on which a locking cap 10 is adapted to slide, this latter is blocked, when in neutral position, by a pin 11 which secures it to a second cap 12 integral with the member 1 serving to guide a striker 13 which is restrained, by means of a spring 15, from a primer 14. The cap 10 is arranged so as to project at the rear of the fuse body 1 carrying the diaphragm 4 which is provided with a recess 16 corresponding with the projection on the cap 10.

Balls 17, or equivalent locking members, are held in engagement with a throat 18 in the striker 13 by the cap 10 which is provided on its interior face, with a throat 19 intended to allow the balls 17 to move out of the way when the fuse is set for action.

A pin 20 connecting the striker 13 with the cap

12 serves, together with the spring 15, to hold the striker away from the primer 14, until the moment of impact.

The arrangement operates as follows:—When the pressure generated in the chamber 5 by the combustion of the reaction or jet propulsion charge 6 attains a predetermined value, the diaphragm 16 is deformed and forces the cap 10 into its bore 9, shearing the pin 11 or other retaining means, the balls 17 being then in position facing the throat 19 are able to move away, by centrifugal force if the projectile is animated by a rotational movement during its trajectory. Otherwise, they are displaced, laterally, on impact, by the striker 13 which impinges, by inertia, against the primer 14, shearing the pin 20 and compressing the spring 15.

Although, in the embodiment described, the fuse is represented as applied to an aerial bomb, it is obvious that, with certain modifications which will be clear to those skilled in the art, it can also be applied to projectiles equipped with a rocket and launched, from the ground, by any kind of instrument, and if desired, fired from a gun like an ordinary projectile, the reaction charge coming into operation either at the time the shot is fired, or during the trajectory, in order to add its effect to the initial launching charge.

It is moreover obvious that various alterations and modifications can be introduced without departing from the scope of the invention as defined by the appended claim.

I claim:

In a rocket-projectile formed with a chamber receiving a jet propulsion charge: a percussion fuse having a fuse body mounted in said projectile, a safety device in said percussion fuse to prevent a premature working of the fuse, said safety device having a locking member projecting from the rear of said fuse body in said chamber, retaining means to maintain said locking member in locking position, a diaphragm interposed between said jet propulsion charge and said locking member, said diaphragm being adapted to be deformed by the pressure generated in said chamber by the combustion of said jet propulsive charge to push said locking member into inoperative position in the fuse body against said retaining means.
